MOSES EWING, OF CHESTER, PENNSYLVANIA, ASSIGNOR OF ONE-HALF TO CHARLES
LESLIE GILLILAND, OF CHESTER, PENNSYLVANIA.

SLUB-CATCHER STOP-MOTION FOR WINDERS.

1,102,214.

Specification of Letters Patent. Patented June 30, 1914.

Original application filed April 1, 1913, Serial No. 758,165. Divided and this application filed August 26, 1913. Serial No. 786,656.

To all whom it may concern:

Be it known that I, MOSES EWING, a citizen of the United States, residing at Chester, in the county of Delaware and State of Pennsylvania, have invented certain new and useful Improvements in Slub-Catcher Stop-Motions for Winders, of which the following is a specification.

My invention relates to improvements in slab-catcher stop motion for winders, and more particularly to an improved slab catching attachment for cone winders, the object of the invention being to provide an efficient slab catcher which will clear the thread, preventing lumps or slubs from passing to the cone and causing the thread to break before permitting a slab or lump to pass.

A further object is to provide a slab catcher comprising two brushes supported at the ends of lazy tongs which are supported in such a manner that when the thread breaks, the brushes will separate and the cone be elevated out of contact with its friction driving roll.

This is a division of my application for patent on improvements in slab catchers, filed April 1, 1913, and given Serial No. 758,165.

With these and other objects in view, the invention consists in certain novel features of construction and combinations and arrangements of parts as will be more fully hereinafter described and pointed out in the claims.

In the accompanying drawings: Figure 1 is a view partly in section and partly in side elevation illustrating my improvements in normal operative position. Fig. 2 is a plan view of the slab catcher *per se*. Fig. 3 is a view similar to Fig. 1 showing the position of the parts when the thread breaks. Fig. 4 is a perspective view of one of the brushes. Fig. 5 is a view in cross section on the line 5-5 of Fig. 2. Fig. 6 is a view in front elevation with the parts as shown in Fig. 1, and Fig. 7 is a perspective view of the wire frame supporting bracket.

My improvements are used in connection with a cone winding machine, and I have illustrated in connection with my improvements, only such portions of the machine as are necessary to illustrate the carrying out of my invention.

1 is a horizontal bar constituting a fixed 55 or stationary part of the machine frame having brackets 2 secured thereon and supporting a shaft 3 containing a roll 4 which is adapted to frictionally turn a cone 5 when the latter rests thereon. This cone 5 is supported by a rotary holder 6 secured to one member 7 of a bell-crank-lever 8 which is pivotally supported on a rod 9 mounted in extensions 10 on brackets 2.

The brackets 2 are made with bearings 11 65 to receive arbors 12 secured in sleeves 13 on a plate 14, and afford pivotal mounting for this plate. Plate 14 is made with posts 15 at its upper end in which a wire guide 16 is secured and over this guide 16, the thread 70 to be wound on the cone is passed, and is directed onto the cone by a guide 17 mounted to slide on a bar 18 and operated by a cam 19, a fragment of the latter being illustrated.

On the lower end of plate 14, a relatively long arm 20 and a relatively short arm 21 are cast integral with the plate and support a rod 22.

A catch 23 is pivotally supported between 80 its ends on the rod 22, and is normally held in an elevated position by a wire frame 24 which is supported in a bracket 25 secured to the plate 14. This wire frame 24 at one end has a crank arm 26 which bears against 85 the shorter end 27 of catch 23, while the opposite end of this wire frame constitutes a horizontal guide 28 under which the cord 17 is positioned and maintained elevated by the cord. As soon as the cord breaks, the 90 frame 28 will fall and permit the catch 23 to fall to the position shown in dotted lines in Fig. 1 into the path of movement of an oscillating trip 29, continuously oscillating with a shaft 30. When the catch falls to 95 this position, the downward oscillating movement of the part 29 will turn the plate downwardly upon its arbors 12 to the position shown in Fig. 3.

The plate is held in its normal operative 100 position by a spring 31 secured on bar 1, and having a curved recess 32 in its free end, which receives a rotary sleeve 33 on a pin 34 fixed in integral ears 35 on the bottom of plate 14. When the plate is pulled downwardly by the oscillator 39, the sleeve 33 will be drawn rearwardly out of the recess 32, and lie in the position shown in Fig. 3.

When again elevated, the recessed end 32 will spring upwardly and hold the parts in normal position as will be readily understood.

5 A frame 36 is pivotally mounted on the rod 22, and is formed at one end with a finger hold 37. This frame when moved upwardly by the finger hold 37 will engage the shorter end of catch 23, hold the same 10 in elevated position, and allow the plate 14 to be raised to operative position without stopping the oscillator 29. In other words, this upward movement of the plate by means of the frame 36, first swings the catch 23 15 out of the path of the oscillator 29, and when the plate is elevated and the cord in operative position with relation to the wire frame 24, the catch will be held in this position.

A toothed bar 38 is connected to bell- 20 crank-lever 8, and extends through a slot 39 in a bracket 40 on one of the posts 15. The teeth of this bar 38 engage the lower wall of the slot 39, so that when the plate 14 falls, bar 38 will be drawn forwardly and elevate 25 the cone 5 out of engagement with roll 4, thereby stopping the turning of the cone. The teeth of bar 38 are inclined or ratchet shaped, so that as the cone increases in diameter, this bar may be moved rearwardly 30 tooth by tooth so that the cone will be elevated regardless of its diameter in the event the thread breaks.

The relatively long arm 20 supports at its free end a short rod 41 on which a table 42 35 is secured. This table 42 at its outer edge has a guide 43 through which the cord 17 is drawn, and on the table a rotary weight 44 is mounted on a vertical post 45 and bears upon the cord to act as a tension device. 40 Between the table 42 and the wire frame 24, the cord passes through my improved slab catcher, which consists of two brushes 46 facing each other and supported in holders 47 fixed to the ends of a lazy tongs 48. This 45 lazy tongs 48 comprises four links as clearly shown in Fig. 2 pivotally connected as shown, and one pivotal connection at the lower end of the lazy tongs consists of a bent rod 49 which is rigidly secured to the 50 frame bar 1, and acts as a stationary pivot for the lazy tongs. The upper pivot 48^a of the lazy tongs comprises a screw which is secured to arm 25^a on bracket 25, so that when the plate 14 moves downwardly, the 55 lazy tongs operates to separate the brushes as clearly shown. The brushes each consist of a backing plate 50 preferably of fabric through which a large number of wires 51 project, forming an extended wire surface. 60 The backing plates 50 are adapted to be slid into and out of the holders 47, so that the brushes may be readily replaced when worn or broken.

When the plate 14 is elevated to opera- 65 tive position, the lazy tongs 48 will bring

the brushes together, engaging the thread 17 with the teeth of the brushes located side by side, that is, the teeth of one brush will project between the teeth of the other brush, and form a circuitous passage for the thread 70 of the thread. In other words, the brushes absolutely insure a clean smooth thread to the cone, and if the slab, lump, or knot is so fixed to the thread that it will not pass 75 through the brushes, the thread will be broken and the parts moved downwardly as above explained, elevating the cone 5 and stopping the operation of winding until the thread is repaired, and the parts moved 80 back into normal position. It will thus be seen that with my improved slab catcher, the dropping of the plate of the frame due to the breaking of the cord, will cause the brushes to separate and when the parts are 85 moved back to normal position, the brushes will come together on opposite sides of the cord, so that the operation of the slab catcher is automatic with the operation of 90 the other parts of the apparatus.

Various slight changes might be made in the general form and arrangement of parts described without departing from my invention, and hence I do not limit myself to the precise details set forth, but consider myself at liberty to make such changes and alterations as fairly fall within the spirit and scope of the appended claims. 95

Having thus described my invention, what I claim as new and desire to secure by Letters Patent is:

1. The combination with a roll, and a winding mechanism above the roll and turned thereby, of a pivoted plate, means for elevating the winding mechanism out 105 of contact with the roll when the plate falls to its lower position, a spring normally holding said plate in elevated operative position, means for drawing the plate downwardly into inoperative position, a catch 110 operated by said means, a wire frame on the plate normally holding the catch out of engagement with the said means, said wire frame held in operative position by the thread to be wound, a slab catcher comprising two brushes engaging the thread in advance of the wire frame, and a support for said brushes compelling the brushes to separate when the plate moves downwardly, substantially as described. 115

2. The combination with a roll, and a winding mechanism above the roll and turned thereby, of a pivoted plate, means for elevating the winding mechanism out 125 of contact with the roll when the plate falls to its lower position, said plate normally elevated and adapted to fall when the thread breaks, a stationary support, lazy tongs connected to the stationary support, and brushes secured to the lazy tongs, said brushes 130

5 moved together when the plate is elevated to engage opposite sides of the thread being wound, and moved apart when the plate falls to inoperative position, substantially as described.

10 3. The combination with a roll, and a winding mechanism above the roll and turned thereby, of a hinged plate, means for elevating the winding mechanism out of contact with the roll when the plate falls to its lower position, and a spring normally holding said hinged plate in elevated position, of an oscillator, a catch on the hinged plate, a wire frame normally holding the 15 catch out of the path of movement of the oscillator, said wire frame held by the cord when the latter is in normal operation, a stationary wire, lazy tongs pivotally connected at one end to the wire and between 20 its ends pivotally connected to the plate, and brushes on the free ends of said lazy tongs normally engaging opposite sides of the thread, substantially as described.

25 4. The combination with a roll, and a winding mechanism above the roll and turned thereby, of a pivoted plate, means for elevating the winding mechanism out of contact with the roll when the plate falls to its lowered position, said plate normally 30 elevated and adapted to fall when the thread

breaks, a stationary support, brushes moved into engagement at opposite sides of the thread when the plate is elevated, and devices compelling the brushes to move apart when the plate falls to inoperative position, substantially as described. 35

5. The combination with a roll, and a winding mechanism above the roll and turned thereby, of a pivoted plate, means for elevating the winding mechanism out of contact with the roll when the plate falls to its lowered position, said plate normally elevated and adapted to fall when the thread breaks, a stationary support, brushes moved into engagement at opposite sides of the 45 thread when the plate is elevated, devices compelling the brushes to move apart when the plate falls to inoperative position, and cord controlled means for holding the plate in an elevated position, whereby said plate 50 is permitted to fall when the cord breaks, substantially as described.

In testimony whereof I have signed my name to this specification in the presence of two subscribing witnesses.

MOSES EWING.
